Patented June 4, 1968

211,237

FOIL PACKAGING TRAY

George J. Buff, Jr., Cherry Hill, N.J. (½ Penny Plate Inc.,
P.O. Box 458, Haddonfield, N.J.)

Filed Dec. 4, 1967, Ser. No. 9,628

Term of patent 14 years

(Cl. D9—219)

Fig. 5.

Fig. 6.

FIG. 1 is a top plan view of a foil packaging tray, showing my new design;

FIG. 2 is a bottom plan view;

FIG. 3 is a side elevational view;

FIG. 4 is an end elevational view;

FIG. 5 is a cross-sectional view on an enlarged scale taken on line 5—5 of FIG. 1; and

FIG. 6 is a cross-sectional view on an enlarged scale taken on line 6—6 of FIG. 1.

I claim:

The ornamental design for a foil packaging tray, as shown.
